UNITED STATES PATENT OFFICE.

ROBERT GREENE, OF BOSTON, MASSACHUSETTS.

IMPROVEMENT IN STREET-SWEEPERS.

Specification forming part of Letters Patent No. 176,623, dated April 25, 1876; application filed March 28, 1876.

To all whom it may concern:

Be it known that I, ROBERT GREENE, of Boston, in the county of Suffolk and State of Massachusetts, have invented an Improved Street-Sweeper, of which the following is a specification:

This invention relates to improvements in machines for sweeping streets, wherein is employed a rotating brush-roller placed diagonally to the direction in which the machine is drawn or moved; and the invention consists in a combination of devices whereby the operator or driver sitting in his seat can readily lift the brush-roller, and also by which the brush-cylinder may be quickly leveled with relation to the road-bed.

Figure 1 represents a top view of one of my improved machines with the seat shown in dotted lines, and in such figure the shafts and gearing under the frame-work are also shown in dotted lines. Fig. 2 represents a side elevation of Fig. 1.

The frame *a* will preferably be made of metal, and the shafts *b* will be securely attached thereto by suitable loops, and on the shafts and frame is placed a frame, *c*. The axle *d*, is sustained by and moves in bearings or boxes secured at each end of the frame *a*, by bolts *e*, and the shaft has fixed to it, outside the ends of the frame, ratchets *f*, that are engaged by pawls on the wheels *h*, the pawls being provided with springs to keep them in engagement with the ratchet-teeth so that when the sweeper is drawn forward the pawls engage the ratchets and turn the shaft *d*, provided with a pinion, *i*, that engages a pinion, *j*, on a shaft, *k*, supported by frame *a*, and provided with a chain or sprocket wheel, *l*, over which passes a chain, *m*, the latter extending also over a sprocket or chain wheel, *n*, on the end of the shaft of the brush or roller *r*, such roller being supported in boxes at the ends of arms *o p*. The arm *o* is shown as made of two pieces of iron, slotted to receive a bolt, *q*, by which to permit the arm to be lengthened or adjusted to keep the chain or belt *m* taut, and the upper end of the arm is pivoted on the end of shaft *k*. The arm *p* is connected at its other end with axle or shaft *d*, and arms *o p* are free to turn about their supporting-shafts *k d*, to raise or lower the brush-cylinder *r*. This

brush is a cylinder provided with holes, in which are placed bunches, preferably of rattan, (about eleven inches in length,) a very durable substance, and one that may be used in wet as well as dry weather, or with dust or mud, and yet work effectually. A metallic or suitable apron or fender, *s*, extends across the machine to stop the dirt thrown off and upward by the brush in its rapid rotation. On the frame and supported in bearings *t* is a rock-shaft, *u*, provided with an arm, *v*, connected by a strap or chain, *l*, with a windlass, *w*, steadied at the top by a brace, *y*, and provided with a crank, *x*, and a ratchet, *z*. The strap on its way to the windlass passes under a sheave, *a'*, and by the crank the windlass may be turned to rock the shaft, and a pawl, *b'*, on the plate *c*, within easy reach of the foot of the driver, who sits on the seat *c'*, may be used to hold or release the windlass at pleasure. On this shaft *u* are arms *d'* connected by adjusting-links *e' f'* with arms of brush-roller-adjusting rock-shafts *g' h'*, provided with other arms *i' j'* that support suitable chains *2 3*, connected with the arms *o p*, and as the rock-shaft *u* is moved it also moves the rock-shafts *g' h'*, and they move the arms supporting the brush-cylinder to lower or raise it to the proper working position with reference to the street, or lift it entirely from the street, as may be desired.

It is necessary to properly sweep a street that the face of the brush-cylinder be placed or held and be turned or revolved with its axis in a plane parallel with the surface of the street being swept, and on some streets one end of the brush-cylinder will be the highest, and on other streets, or perhaps on the same street, but in going in the opposite direction, it is necessary to have the other end of the brush the highest.

To adjust the brush parallel with the street, and to do it quickly, I place on the links *e' f'*, two nuts, *4 5*, one at each side of a pivoted hub on the arms of the shafts *g' h'*, and by moving these nuts on the screw-threads cut on the links, I can change the position of the rock-shafts *u g' h'* with reference to each other to have either end of the brush-roller lifted more or less.

My machine is very light as compared with most street-sweeping machines, can be easily

managed by a single horse and one man, and the driver from his seat on the sweeper can easily make all his adjustments and lift or lower the brush-cylinder out of or into working position.

The bar *o* might be in one piece and have other means provided by which to tighten the driving-belt.

An ordinary friction-clutch might be used instead of the ratchet.

I claim—

1. The brush-roller and its pivoted supporting-arms, in combination with the connected rock-shafts *u* *g*' *h*', to raise and lower the brush-cylinder, substantially as described.

2. The rock-shaft *u*, and connected rock-shafts joined with the brush-roller frame, in combination with the strap and windlass adapted to move the rock-shaft and brush-roller vertically.

3. The rock-shaft *u*, and rock-shafts *g*' *h*', and adjustable connecting-links *e*' *f*', substantially as subscribed.

In testimony whereof I have signed my name to this specification in the presence of two subscribing witnesses.

ROBERT GREENE.
